UNITED STATES PATENT OFFICE.

CARL SCHWARZ, OF CHARLOTTENBURG, NEAR BERLIN, GERMANY, ASSIGNOR TO WESTINGHOUSE ELECTRIC & MANUFACTURING COMPANY, A CORPORATION OF PENNSYLVANIA.

INDUCTIVE ARRANGEMENT FOR SIGNALING OVER POWER LINES.

Application filed October 31, 1921. Serial No. 511,833.

To all whom it may concern:

Be it known that I, CARL SCHWARZ, a citizen of Germany, residing in Charlottenburg, near Berlin, Germany, have invented a new and useful Improvement in an Inductive Arrangement for Signaling Over Power Lines, of which the following is the specification.

This invention relates to arrangements for imposing currents of radio-frequency upon the line wires of a power-transmission system or for inductively receiving radio-frequency currents from such a line.

It is an object of this invention to provide a means whereby the signal-sending or receiving conductor may be supported in proximity to one wire of the transmission line without being near other wires of the line.

It is a further object of this invention to provide an inexpensive and convenient means for supporting the supplementary conductor and for supporting a portion of a one line conductor in proximity thereto.

It is a further object of this invention to accomplish the object just stated with a minimum number of masts.

It is a further object of this invention to provide one wire of the transmission line with a loop located at one side of the line and to support a loop of the auxiliary conductor adjacent to the loop in said wire.

These and other objects of my invention, as well as the details of construction by which my invention is to be practiced, will be more fully disclosed by the following description and the accompanying drawing, wherein

A single figure is a view, partly diagrammatic and partly in perspective, of the arrangement of wires and supports used in my invention.

The transmission line *k* is made up of a number of wires, ordinarily as many as the phases, which are supported from the masts or other similar supports by the usual arrangement of cross wires and strain insulators or by the usual cross arms. At any convenient point in the line where it is desired to impress upon it radio-frequency current or to receive radio-frequency current from the line, a mast *m* is located at one

side of the line and two masts *h*, a distance apart, upon the other side of the line. From the mast *m* a pair of stay wires, each provided with the necessary strain insulators, go to two points upon one of the wires of the transmission line. The points at which these stay wires support the wire *l* are separated by a distance dependent upon the distance which the loop, described below, is located to one side of the transmission line.

The two masts *h* are each supplied with a stay wire and these wires have strain insulators. The stay wires are connected to the line wire *l* at the points *a* and *b* so that the wire *l* is held in the form of a triangular loop at one side of the transmission line. Where this wire appears in the drawing to cross, forming the point of the triangle nearest the line, one portion of the wire is supported at a somewhat greater height than the other so that the loop in the wire *l* is not in danger of being short circuited by any motion of the wires due to wind or other disturbing causes.

The mast *m* carries a third stay wire which is also provided with insulators and supports the nearest point of a second loop *s*. The masts *h* are also provided with auxiliary stay wires and support the other two corners of the loop *s*. From any convenient point on this loop *s* lead wires go to the signal sending or signal receiving apparatus. Since this loop constitutes the means by which energy leaves the signaling apparatus to be sent along the line or the means by which signaling energy leaves the line to be received in the signaling-receiving apparatus, the loop *s* may be properly called an antenna.

It is obvious that either one of the wires in the transmission line *k* may be chosen instead of the wire *l* so that any phase of the transmitted power may be used to supply the loop. It is also obvious that, if desired, different wires in the transmission line may be formed into such loops at different points along the line and, also, that other lines beside power-transmission lines may be supplied with such loops if desired.

I claim as my invention:

1. In a power-transmission line comprising a number of line wires, means for supporting one of said line wires at separated points, supporting means at one side of the transmission line, a loop in said wire, extending between said separated points and supported in part by said supporting means at one side of the line, and a loop distinct from said line wire inductively related to the first-named loop.
2. In a power-transmission line comprising a number of line wires, means for supporting one of said line wires at separated points, supporting means at one side of the transmission line, a loop in said wire, extending between said separated points and supported in part by said supporting means at one side of the line, a looped antenna and auxiliary supporting means for maintaining said looped antenna in proximity to said line wire loop.
3. In a transmission-line system, a mast at one side of the line and a plurality of masts at the other side of the line, means

extending from the first named mast for supporting one wire of the transmission line at two separated points, a polygonal loop in said line wire and means extending from each of the other masts for supporting said polygonal loop, said loop having as many corners as there are masts.

4. In a transmission-line system, a mast at one side of the line and a plurality of masts at the other side of the line, means extending from the first named mast for supporting one wire of the transmission line at two separated points, a polygonal loop in said line and means extending from each of the other masts for supporting said polygonal loop, said loop having as many corners as there are masts, auxiliary supporting means extending from each of said masts and a polygonal antenna loop supported by said auxiliary supporting means in inductive relation to said first named loop.

In testimony whereof I affix my signature.

CARL SCHWARZ.
